NET SUPPORTING ARRANGEMENT
Eugene M. Respini, 2725 Brownboro Road,
Louisville 6, Ky.
Filed Feb. 1, 1962, Ser. No. 170,385
3 Claims. (Cl. 273—181)

This invention relates generally to an arrangement for suspending a net or other sheet means in a generally upright position for impeding the flight of balls or other sport related flying objects.

While the invention may be employed in various games and practice sessions related thereto which require a net or the like to be suspended in a generally upright position, the invention is particularly well suited for use as a close range golf practice target. Hence, it will be described in this connection primarily although, as the following proceeds, the utility of the invention in other applications such as badminton, baseball practice, etc., will become readily appreciated by those skilled in the art.

The objects of the invention include the provision of a net supporting structure adapted for quick and easy assembly and dismantling, adapted for either indoor or outdoor use, comprised of parts which in unassembled relation may be stored in a compact package, and which, in service, performs its intended function in a very satisfactory manner.

In accordance with the broader aspects of the invention, the arrangement comprises a flexible net or sheet supported in a generally upright position by a pair of opposite side poles having their upper ends connected to the respective upper corners of the net and having their bottom ends supported by base means urging the poles in opposite, generally outward directions so that the upper ends of the poles must be deflected inwardly to a substantial degree to assume their connected positions. As a result, the poles exert a substantial outward force on the upper corners of the net so that inordinate sagging of the net is prevented without any requirement for guy lines, or horizontal cross bars along the upper edge of the net. Preferably the frame assembly members are separable, in part segmented, and include telescopic joints so that in disassembled relation the parts may be stored in a compact package.

Where the arrangement is supported on a surface which is not to be penetrated by any part of the structure, the bottom ends of the side poles are supported by base elements spaced apart by a cross member. Preferably the distance is substantially less than the width of the net. The bottom corners of the net are attached to forwardly and outwardly extending legs, and intermediate portions of the net bottom horizontal margin, which preferably is weighted by means of a sand tube so as to seat firmly, are connected to, and drawn rearwardly toward, the base elements to create tension in the lower horizontal margin of the net. This arrangement results in the whole frame structure of easily separable elements being more or less locked together by the forces created in the frame and resisted by the net and yieldable connections.

Where the arrangement is to be supported upon a surface which may be penetrated, such as the earth or ground, the same net and side poles are used, but ground stakes support the bottom ends of the side poles and the side edges of the net are yieldably connected to the side poles at several points below the upper ends. The ground engaging stakes are so constructed that while they are subject to a substantial rotational force due to the inward deflection of the poles required to make the net connection, they maintain their original position sufficiently, even in relatively soft ground, that no guy lines are required.

2

These and other features will be considered in some detail in the following.

The invention will be described in connection with preferred embodiments incorporating the principles of the invention by way of example and illustrated in the accompanying drawing wherein:

FIGURE 1 is a front view of an outside arrangement embodying the invention;

FIGURE 2 is an enlarged isometric view of a preferred ground stake for use in the FIGURE 1 arrangement;

FIGURE 3 is a fragmentary view of a telescopic joint; FIGURE 4 is a front isometric view of a free standing arrangement embodying the invention and particularly adapted for inside use;

FIGURE 5 is a fragmentary, exploded, enlarged isometric view of a portion of the base means of the FIGURE 4 arrangement; and

FIGURE 6 is a front view illustrating the invention embodied in an arrangement supporting a net of type used in volley ball and badminton.

The outside arrangement, i.e., wherein the supporting surface for the assembly may be penetrated, will be described first. The assembly shown in FIGURE 1 includes a net 10 supported in a generally upright position by the opposite side poles 12 which in turn have their bottom ends connected to ground stakes generally designated 14. The side poles, before being attached to the edges of the net, are disposed as illustrated by the broken line representations thereof. When connected to the upper corners of the net, the upper ends of the side poles are deflected inwardly to assume the bowed positions illustrated. While the means for connecting the upper corner areas of the net to the upper ends of the side poles may take various forms, one satisfactory form is a ring fixed to the net and adapted to be slipped over the upper end of the side pole to engage with detent means to prevent the ring from slipping either up or down.

It is preferable in connection with the outside arrangement that the vertical sides of the net be connected to the side poles at the bottom and at intermediate points, and that these connections be elastic in nature to enhance the overall yieldability of the net and frame structure when the net is struck by a high speed flying object. To this end, rings 18 attached to the side edges of the net and having heavy rubber bands 20 looped therethrough and around the poles may be used.

To insure that the bottom edge of the net seats firmly upon the ground or other supporting surface, a flexible tube 22 containing sand or some other relatively heavy granulated material is fastened along the bottom edge. This arrangement minimizes the possibility that a ground ball will pass thereunder.

One net material found to be satisfactory for use as a golf target is a woven nylon mesh having about $\frac{1}{8}$ " square openings framed by the nylon filaments.

The side poles 12 are preferably flexible in the sense that they may be deflected inwardly to a substantial degree without the poles taking any appreciable permanent set while connected to the net. Thus the outward force exerted on the net by the poles prevents inordinate sagging of the net. One material found to be quite satisfactory in this respect, and also from the standpoint of light weight, is high tensile aluminum tubing.

For facilitating the packaging of the dismantled assembly in compact form, the side poles 12 are made up of separable segments which are joined or connected in telescopic relation to each other. A simple telescopic joint wherein a reduced diameter end of one segment 12a slips into a mating end of another segment 12b, as illustrated in FIGURE 3, is satisfactory for purposes of the present invention. Close tolerances in these joints are not re-

quired since the joints are effectively locked when the side poles are deflected inwardly for attachment to the net.

A significant aspect of the invention is that the bottom ends of the side poles 12 be supported in a manner which urges the side poles in opposite outward or lateral directions away from the edges of the net so that the outward forces so exerted prevent inordinate sagging of the net. This is attained in the outside version, without the aid of guy lines, by using base means in the form of ground stakes of the type illustrated in FIGURE 2.

The ground stake 14 has the general shape of an inverted J with respect to its ground contacting portion and includes a main leg 24, a parallel auxiliary leg 26 of somewhat shorter length, a generally flat horizontal cross piece 28 perpendicular to and joining the main leg and the auxiliary leg, and an upwardly projecting stem 30 located at the main leg and cross piece junction. In its preferred form the main leg includes a thickened portion 32 extending along its longitudinal axis and includes diametrically opposite, extended-surface flanges 34 which, when the ground stake is forced into the ground, are disposed in a plane normal to the plane of the net. The thickened portion 32 of the main leg is tapered downwardly toward a point, and the opposite flanges 34 are also brought toward a point at the bottom end of the leg. The auxiliary leg 26 has a form very similar to the main leg, but is considerably shorter than the main leg. The cross piece 28 has a thickened axially extending portion or rib 36 underlying its diametrically opposed flanges 38 which are disposed in a horizontal plane when the stake is forced into the ground. The stem 30 has its longitudinal axis tilted outwardly relative to the axis of the stake main leg 24 so that when the side poles 12 are telescopically joined to the ground stakes by slipping the bottom ends of the side poles over the stem the side poles will assume the broken line positions of FIGURE 1 until deflected inwardly and attached to the net. The ground stakes are preferably a cast shape, and may be made of aluminum for lightness.

When the outside arrangement is to be erected, the ground stakes 14 are forced into the ground with a spacing therebetween determined in accordance with the width of the net. The ground stakes are disposed in mirror relation to each other with the auxiliary legs inside the main legs. It will be appreciated that extended-surface flanges of each part of the J-shaped structure, i.e., the main leg, the auxiliary leg, and the cross piece, serve as pressure receiving surfaces which resist the tendency of the ground stakes to rotate about a horizontal line due to the moment created by the inward deflection of the respective side pole.

It is to be noted that the ground stake of the invention is rather easily forced into rather hard ground by employing a combination of a downward force exerted on the cross piece 28 and a circular or rocking motion imparted to the main leg 24 as will now be described. In forcing the ground stake into the ground, a segment of a side pole 12 is joined to the stem 30 by slipping it thereover, a downward force is exerted by stepping on the cross piece 28, and at the same time, if necessary, the upper end of the side pole segment is moved about to cause the main leg to open its own path into the ground. This effect may be obtained to a lesser, but sufficiently effective degree, even after the auxiliary leg has begun to enter the ground.

It will be appreciated that the form of ground stake herein described may be employed for purposes other than supporting a game target or the like. For example, it might be used alone for anchoring guy wires. It may also be provided with another set of diametrically opposite flanges (not shown), also axially extending, on each leg, for all or part of the length of the legs, and at right angles to the other flanges, to enhance resistance to rotation of the stake in the other direction.

Passing now to the indoor form of the assembly, i.e., the form adapted to be free standing upon a horizontal surface wherein no part of the assembly penetrates the surface, the principles of the invention are equally incor-

porated in this assembly, but with certain modifications being made to accommodate the changed supporting condition. The same net 10 and side poles 12 are used for the indoor assembly, but in the preferred arrangement the base means supports the bottom ends of the side poles with a space therebetween substantially less than the spacing between the bottom ends of the side poles when supported by the ground stake. As in FIGURE 1, the broken line position of the side poles corresponds to their position when unattached to the upper corners of the net.

The frame portion of the indoor assembly may be characterized as including two generally U-shaped portions with the bight of each portion being a common horizontal member 40. The upwardly open U-shaped portion includes the two side poles 12 forming the legs of the larger U, and the horizontal member 40 forming the bight of the larger U. The same horizontal member forms the bight of the smaller U which is forwardly open and includes the opposite members or legs 42 which project forwardly and outwardly from the respective opposite ends of the bight.

The hubs generally designated 44 which serve to connect the various legs and bight of the U-shaped portions of the assembly are shown in FIGURE 4. One hub is provided at each end of the horizontal member 40. The spoke 46 is telescopically received within one open end of the horizontal member 40, the spoke 48 disposed at an obtuse angle relative to spoke 46 is telescopically received within the open bottom end of one of the side poles 12, and the spoke 50 is telescopically received within an open rearward end of one of the forwardly and outwardly extending members 42. A bottom vertical leg 52 is provided for each hub to elevate the bight or horizontal member 40 above the surface on which the assembly is supported so that when the upper ends of the side poles are deflected inwardly for attachment to the upper corners of the net, sufficient space is provided for the horizontal member 40 to bow downwardly without contacting the supporting surface for the assembly. By elevating the horizontal member 40 with the legs 52, the upwardly open U-shaped portion of the frame is tilted forwardly so that the center of gravity of the entire assembly is shifted forwardly to a stable position. In this connection it is noted that the spokes 46 and 48 and the leg 52 have their axes in a common plane.

The bottom corners of the net are secured to the respective forward ends of the legs 42. The net intermediate side connecting means 18 and 20 are not used in the indoor assembly. However, at several points along the bottom edge of the net, the bottom edge is connected by elastic bands 54 to the vertical legs 52 of the respective hubs as shown in FIGURE 4 so that the lower portion of the net assumes a shape which includes wing-like portions on the sides. This substantially minimizes the tendency of a ball which strikes near the side edge of the net from rolling off the edge and passing beyond the net.

While it is not essential that the spacing between the hubs 44 of the indoor assembly be substantially less than the spacing between the stakes 14 of the outdoor assembly, this is the preferred arrangement. In this preferred arrangement, the outward inclination of the bottom ends of the side poles is greater than in the outdoor arrangement, but since the hubs are inwardly of the side edges of the net and are elevated above the supporting surface, this is compensated for.

It will also be seen that the indoor assembly provides an arrangement wherein substantially all of the supporting frame for the net is shielded by the net. While this feature does not obtain with the outdoor assembly, it is noted that in the outdoor assembly as shown in FIGURE 1 there is an absence of both an upper and lower horizontal member, and the side poles are, for most of their length, spaced somewhat away from the side edges of the net.

In both the indoor and outdoor arrangements the suspension of the net may be characterized as being gen-

erally yieldable since the frames have an inherent spring in them, the connections between the net and frame are for the most part elastic in nature, and no guy lines need be used. Thus the high velocity impact of a ball is readily absorbed by the yieldability of the arrangement 5 so that high velocity rebound is avoided.

The described arrangements made up of separable parts supporting a seven foot by nine foot net, for example, may be conveniently packaged in dismantled form in a cloth bag or the like which fits into a box having dimensions of 10 about 30 inches by 6 inches by 5 inches. The apparatus may be set up or taken down rapidly, such as in less than 5 minutes, by one acquainted with the structure.

FIGURE 6 illustrates the invention embodied in a badminton net and support, and is not deemed to require 15 further comment, except that parts of the same general character as in FIGURES 1 and 3 are designated by the same numerals.

While it has been noted that it is preferable that the hubs in the indoor arrangement (FIGURE 4) be spaced 20 apart substantially less than the width of the net, perhaps some of the reasons for this preference should be explained. The inward deflection of the side poles 12 revolves the hubs 44 to a slight degree and thus causes the cross member 40 to bow downwardly as shown. If the 25 cross member is as long as the net is wide, the deflection of this member may cause its middle portion to contact the floor and possibly raise the vertical legs of the hubs off the floor. Additionally, since a shorter cross member is more resistant to deflection than a long one, the outward force at the upper ends of the side poles is generally greater with a shorter cross member than with a longer one, assuming all other relationships to be the same.

Having described my invention, I claim:

1. Apparatus of the character described, comprising:
(a) sheet means adapted to be supported in a generally upright position to impede the flight of an object;
(b) a pair of opposite side poles connected at their

upper ends to the respective upper corners of said sheet means;

- (c) base means including joint means co-operable with the bottom ends of said poles to mount said bottom ends in oppositely directed, substantially outwardly tilted dispositions with said pole upper ends being spaced substantially outwardly from said upper corners of said sheet means before said upper end connections are made, said pole upper ends being deflected inwardly to a substantial degree in connected relation with said sheet means;
- (d) said base means comprise a pair of inverted J-shaped ground stakes adapted to be forced into the ground in spaced-apart mirror relation to receive the respective bottom ends of said side poles;
- (e) the main legs and short legs of said stakes including extended-surface, ground-engaging portions disposed in generally vertical planes substantially normal to the plane of said sheet means.

2. The apparatus of claim 1 wherein:

- (a) said joint means includes means adapted to be telescopically connected to the bottom ends of said side poles and having its axis tilted outwardly relative to the axis of said main leg.

3. The apparatus of claim 1 wherein:

- (a) each of said side poles is comprised of at least two separable sections including telescopic joint means for joining said sections.
